CLAIM

We claim the ornamental design for a wireless animal receiver collar, as shown and described.

DESCRIPTION

FIG. 1 is a perspective view of a wireless animal receiver collar showing our new design, the portion in phantom lines representing a buckle forming no part of the claimed invention;

FIG. 2 is a front view thereof;

FIG. 3 is a rear view thereof;

FIG. 4 is a side view thereof;

FIG. 5 is another side view thereof;

FIG. 6 is another side view thereof, opposite the view shown in FIG. 4; and,

FIG. 7 is another side view thereof, opposite the view shown in FIG. 5.
